UNITED STATES PATENT OFFICE.

FRANK CERAR AND JOHN OGRINC, OF BROOKLYN, NEW YORK.

RESILIENT SHOE-HEEL.

1,261,488.

Specification of Letters Patent.

Patented Apr. 2, 1918.

Application filed November 17, 1917. Serial No. 202,464.

To all whom it may concern:

Be it known that we, (1) FRANK CERAR and (2) JOHN OGRINC, (1) a citizen of the United States of America and (2) a subject 5 of the Emperor of Austria, (having declared his intention to become a citizen of the United States,) residing at Brooklyn, in the county of Kings and State of New York, have invented certain new and useful 10 Improvements in Resilient Shoe-Heels, of which the following is a specification.

This invention relates to certain new and useful improvements in resilient shoe heels.

The primary object of the invention is the 15 provision of a heel for boots and shoes adapted for imparting resiliency thereto for ease in walking, a suitable adjustable tensioning means being arranged.

A further object of the device is the 20 provision of a shoe heel having an adjustable mechanical spring member obscured from view in such a manner as to present the external appearance of the usual shoe heel.

A still further object of the invention is 25 the provision of a shoe heel that is easy and inexpensive to manufacture and arranges a regulated resiliency for the heel portion of a shoe, the device being easily assembled and positioned upon a shoe as well as disassembled for purposes of repair when required.

In the drawing forming a part of this 30 application and in which like reference characters refer to corresponding parts throughout the several views,

Figure 1 is a central longitudinal sectional view through the device arranged upon a shoe,

Figs. 2, 3 and 4 are transverse sectional views taken respectively upon lines II—II, 40 III—III and IV—IV of Fig. 1,

Fig. 5 is a similar sectional view of a form 45 of the device, arranged for men's shoes and

Figs. 6 and 7 are sectional views taken upon line VI—VI and VII—VII of Fig. 5.

Referring more in detail to the drawing, 50 a shoe 10 is illustrated having the usual outer sole 11 and an inner sole 12, the device in the form of a heel 13 being detachably secured to the heel portion 14 of the sole 11.

A mounting plate 15 is arranged substantially conforming to the lower face of the heel portion 14 and is secured to the latter by screws 16 passing through the outer sole 11 from the interior of the shoe 10 and 55 threaded into bosses 17 of the plate 15,

A tubular depending portion 18 is provided on the plate 15, open at both ends but having a transverse partition 19 arranged parallel to the tread of a heel 13. A bushing 20 is arranged within the tube 18 while 60 a sleeve 21 telescopes within the bushing 20 and is adapted to slide longitudinally thereof. A stop-key 22 is provided upon a strip 23, the said key being arranged through alining openings 24 and 25 in the tube 18 65 and bushing 20 respectively, while the key also extends within a longitudinal slot 26 in the sleeve 21 for limiting the relative movement between the said sleeve and bushing.

An annular flange 27 is arranged at the free bottom end of the sleeve 21 adapted to receive a tread plate 28 and a tread surface or block 29 secured to the lower face thereof by means of screws 30. A flexible covering 31 preferably formed of leather similar to the construction of the shoe 10, is secured around the flange 27 and the plate 15, completely inclosing the heel spring mechanism and held in place at its upper end between 70 the plate 15 and the sole portion 14 and at its lower end between the flange 27 and the tread-plate 28.

A helical spring 32 is centrally arranged 75 within the bushing 20 between the partition 19 and the bottom 33 of the sleeve 21, whereby resiliency is given to the structure. A hollow post 34 is arranged upon said bottom 33 encircled by the spring 32 while a tensioning screw 35 is swiveled through the 80 top 36 of the post 34 and centrally threaded through the partition 19. The chamber 37 in the upper end of the tube 18 above the partition 19 accommodates the free end of the screw 35 and it will be understood that 85 by moving the screw upwardly, in its threaded engagement with the partition 19, by turning the head 38 of the screw, the tension of the spring 32, will be increased while the lowering of the screw by reversing the 90 direction of rotation, thereof, would decrease the tension upon the said spring.

A dished spring washer 39 surrounds the 95 sleeve 21 and is mounted upon the flange 27 so that any excessive upward movement of the said sleeve will seat the tube 18 and bushing 20 upon the washer 39, thereby absorbing the shock of any excessive load such as that exerted by jumping, the washer 39 being also serviceable in the event of the 100 105 110

breaking of the spring 32. This form of heel 13 is especially adapted for women's shoes.

In Figs. 5, 6 and 7 a modified form of 5 spring heel 40 is provided arranged upon a shoe 41 having a sole 42, the same consisting of a plate 43 secured to the sole 42 by screws 44 and having a tread-member 45 resiliently spaced beneath the plate 43 by 10 a plurality of helical springs 46. The springs 46 are positioned in circular sockets 47 arranged in the adjacent faces of the plate 43 and tread-member 45 while a leather covering 48 incloses the mechanism 15 being secured at its upper end between the sole 42 and the plate 43 and at its lower end between the tread-member 45 and a disk 49 of the tread block 50, securing screws 51 being arranged between the members 49, 20 50 and 45.

Limiting links 52 are arranged centrally of the springs 46 with their lower ends arranged with cross-pins 53 extending therethrough carried by the tread-member 45 25 within openings 54 arranged in the said tread-member. The upper ends of the links 52 are provided with similar pins 55 transversely carried by sleeves 56 threaded in openings 57 in the plate 43. It will be seen 30 that the shoe 41 is cushioned by means of the springs 46 while their tension is initially set and determined by positioning the sleeves 56, the entire structure possessing great strength and durability.

35 What we claim as new is:—

1. A spring heel comprising an attaching plate, having a depending tube, a partition arranged intermediate the ends of the tube, forming an upper chamber therein, a sleeve 40 telescoping within the tube, a spring positioned between the sleeve and partition, a tensioning screw for the spring having journaled connection with the sleeve and adjustably threaded through the partition projecting into the said chamber, and a tread-member upon the lower end of the sleeve.

2. A spring heel comprising an attaching

plate, having a depending tube, a partition arranged intermediate the ends of the tube, forming an upper chamber therein, a sleeve 50 telescoping within the tube, a spring positioned between the sleeve and partition, a tensioning screw for the spring having journaled connection with the sleeve and adjustably threaded through the partition projecting 55 into the said chamber, the said tube having an opening therethrough, and the sleeve having a longitudinal slot adjacent the opening and of greater length than the opening, a movement limiting key carried 60 by the tube, extending through the opening thereof and into the said slot, a flange upon the lower end of the sleeve, and a tread-member secured to the said flange.

3. A spring heel comprising an attaching 65 plate, having a depending tube, a partition arranged intermediate the ends of the tube, forming an upper chamber therein, a sleeve telescoping within the tube, a spring positioned between the sleeve and partition, a 70 tensioning screw for the spring having journaled connection with the sleeve and adjustably threaded through the partition projecting into the said chamber, the said tube having an opening therethrough, and the 75 sleeve having a longitudinal slot adjacent the opening and of greater length than the opening, a movement limiting key carried by the tube, extending through the opening thereof, and into the said slot, a flange upon 80 the lower end of the sleeve, a tread-member secured to the said flange, a dished spring-washer surrounding the sleeve arranged upon said flange beneath the free end of the tube and a flexible covering surrounding 85 the spring tube and sleeve with its upper end secured between the plate and sole and its lower end retained between the said flange and tread-member.

In testimony whereof we affix our signatures.

FRANK CERAR.
JOHN OGRINC.
